UNITED STATES PATENT OFFICE.

RUSSEL FRISBIE, OF CROMWELL, CONNECTICUT, ASSIGNOR TO THE J. & E. STEVENS COMPANY, OF SAME PLACE.

DESIGN FOR A TOY BANK.

SPECIFICATION forming part of Design No. 20,646, dated March 31, 1891.

Application filed March 5, 1891. Serial No. 388,910. Term of patent 3½ years.

To all whom it may concern:

Be it known that I, RUSSEL FRISBIE, a citizen of the United States, residing at Cromwell, in the county of Middlesex and State of Connecticut, have invented and produced a new and original Design for Toy Banks, of which the following is a specification, reference being had to the accompanying drawings, forming a part thereof.

10 Figure 1 is a perspective view of the toy bank. Fig. 2 is a detail plan view of the top of the bank. Fig. 3 is a detail plan view of the bottom of the bank.

The leading features of my design, as shown 15 in the perspective view of the structure, consist in its shape and conformation, that are in general that of a box having flat sides. On one side of this box-like structure is a front *a*, the larger surface formed as a sunken 20 panel, with minor panels *b c* extending across the top and bottom and perforated by openings, those at the end of the minor panels being oblong, while between the oblong openings are the heart-shaped openings, the points 25 of the heart-shaped figures turning toward

each other. The side *d* of the structure is divided into a series of panels by crosswise lines and is pierced by openings *e* of diamond shape, and at the sides, top, and bottom there is a V-shaped opening *f*, completing the diamond pattern. The top *g* of the structure is divided into two panels, each perforated at the center with a diamond-shaped opening and at the opposite ends with the heart-shaped openings. The front of the structure bears the 30 word "Safe" displayed in suitable letters.

What I claim is—

The design for a toy bank, consisting of the box-like structure having on the front the sunken panel with minor panels perforated 40 by the oblong and heart-shaped figures, a side formed in panels with diamond and V shaped openings, and a top formed in panels with the diamond and heart shaped openings, as shown and set forth.

RUSSEL FRISBIE.
